UNITED STATES PATENT OFFICE

CHARLES H. MACDONALD, OF SAN FRANCISCO, CALIFORNIA

ROD MILL

Application filed April 4, 1930. Serial No. 441,511.

This invention relates to improvements in rod mills and more particularly to mills for reducing pulp and fibrous products.

Among the objects of the invention are to 5 simplify the structure and increase the efficiency of this class of mills.

Another object is to improve the feed and distribution of products passing into and through the mill.

10 Another object is to insure the positive and uniform operation of the crushing rods.

A further object is to reduce the interstitial displacement of the rods.

15 Other objects and advantages will appear as the description progresses.

In this specification and the accompanying drawings the invention is disclosed in its preferred form. But it is to be understood that it is not limited to this form because it may 20 be embodied in other forms. It is also to be understood that in and by the claims following the description it is desired to secure this invention in whatsoever form it may be embodied.

25 In the three sheets of drawings:

Fig. 1 is a plan view from above of a rod mill constructed and arranged in accordance with this invention.

Fig. 2 is an enlarged detail in vertical cross 30 section of the same, taken on the line II—II.

Fig. 3 is a longitudinal vertical section of the same, taken on the line III—III.

Fig. 4 is a diagrammatic end elevation partially in vertical section, showing a modified 35 application of the rod mill submerged in a vertical tank having a screening and circulating system.

In detail the construction illustrated in the drawings, referring to Fig. 1, comprises an 40 enclosing casing or tub 1, having the longitudinal partition 2, extending upward from the bottom 3 thereof.

The segmental apron 4, extends transversely 45 between the partition 2 and the adjacent side wall 5, and upward from the bottom 3. From the apex 6 the apron slopes down to the bottom 3 again. This arrangement creates a substantially circular path for the flow of pulp when propelled by the rod mill.

50 The rod mill comprises the flanged cylin-

drical drum 7, with the heads 8 and 9 bolted to the flanges at 10—10. The head 8 is a flat disc fixed to the end of the shaft 11. The opposite head has the hollow trunnion 12, closed by the flanged cap 13 bolted thereto. The end 14 of this cap is flush with the inner plane of the head 9.

55 The shaft 11 and trunnion 12 are journaled in suitable bearings in the pillow blocks 14 and 15 on the floor on opposite sides of the tub 1. The drum is driven in any suitable manner and revolves between the partition 2 and the wall 5, adjacent the apron 4, the curve of which is concentric with the periphery of the drum.

60 The drum has the series of interspaced openings 16 separated longitudinally by the bars 17—17 and circumferentially by the bands 18—18, making in effect a peripheral integral grid work surrounding the openings 70 16. For greater rigidity the bands 18—18 are channel or T shape in cross section.

65 The lugs 19—19 are cast integrally with the bands 18—18. The fly bars 20—20 are secured between these lugs 19—19 by the bolts 75 21. The ends of the fly bars rest within notches formed in the flanges 10 and the heads 8—9.

70 The interior of the drum is provided with the annular rows of elevators 22—22 consisting of a series of humps or corrugations which have a biarcuate contour. These are preferably formed in segments containing three or more humps, depending upon the diameter of the drum. These segments are 80 preferably alined with the bands 18—18 through which they are bolted by the bolts 23, the heads of which are countersunk into the segments, with the nuts bearing against the outside of the bands 18.

85 These elevators are arranged in longitudinal alinement with the openings 16 so that the rods 24 cannot obstruct free passage of pulp through the openings 16.

90 The rods 24—25 lie within the drum parallel with the axis of the shaft 11, from end to end of the drum, with a slight end play. The heads 8—9—14 have the liners 26 fixed thereto to take the wear incidental to the end thrusts of the rods. The rods 25 are 95 100

smaller in diameter for greater interstitial efficiency, the smaller rods reducing the interstices 27', existing between the larger rods 24. The rods are introduced into and removed from the drum through the hollow trunnion 12, closed by the cap 13.

The present embodiment of this invention adapts it particularly to the grinding, squeezing and maceration of wood pulp and the like. The pulp in liquid suspension is introduced into the tub 1, up to the desired level. This submerges the lower portion of the drum.

Referring to Fig. 2, the drum is revolved 18 contraclockwise. The semi-fluid pulp is elevated by the fly bars 20 cooperating with the apron 4 and descends through the holes 16 into the drum among the rods 24-25. In the initial stages the pulp may be coarse and 20 heavy and filled with slabs and chunks of "lap" or compressed pulp. These striking the baffle bar 27 fixed to the cover 28, across the width of the drum, aids in forcing the pulp into the drum through its periphery.

25 The rotation of the drum causes the rods to tumble downward from the internal periphery of the drum, whence they are raised by the elevator humps 22. The rounding off of the humps 22, as shown, minimizes the 30 wear on the rods 24-25. These tumbling rods roll upon each other, crush, squeeze, and grind the pulp therebetween finer and finer as the operation continues, until the desired reduction is attained.

35 The pulp in excess of the capacity of the holes 16 is pushed up the apron 4 and over the apex 6. This sets up a circulation of the pulp on the opposite side of the partition 2 and back through the mill until the 40 grinding of the batch of pulp is finished.

The initial grinding is facilitated by the addition of the shear bars 28' fixed across the lower portion of the apron 4. These cooperate with the fly bars to shear and tear up the 45 "laps" or chunks of pulp.

The general characteristics of the mill shown and described are equally advantageous for dry grinding, by modifications in the means for feeding and discharging the 50 product into and from the mill. The inlet and outlet from the mill are through the periphery of the drum, as distinguished from mills fed and discharged axially through hollow shafts.

55 The modification shown in Fig. 4 comprises the mill of the general construction above described in detail, located in the bottom of the tank 29.

This tank may be of any conventional construction, having the semi-cylindrical bottom 30, conforming to the periphery of the mill, and in approximate contact with the fly bars 20.

The bottom of the tank has the sump 31 extending the length of the mill across the bot-

tom of the tank. The bottom of the sump is formed by the plate 32 bolted to the tank 29. The discharge nipple 33 is screwed into this plate and has the draw-off valve 34 for withdrawing the milled pulp.

The screen 35 rests upon the plate 32 and is curved concentrically with the bottom of the tank. The fly bars in this instance may be strips of hard wood so as not to wear the screen 35 should they contact it. They constantly sweep the surface of the screen to keep its meshes open when pulp is being drawn off from the sump beneath.

70 After the initial breaking up of the pulp in the tank 29, the valve 36 may be opened 80 to the pump 37, which sucks the pulp 31 through the pipe 38 and discharges through the pipe 39 back into the top of the tank 29.

The bypass 40 at a lower level on the tank has a valve 41 which may be opened to short 85 circuit the discharge from the pump 37 after the coarse pulp has been broken up.

The vertical tank arrangement in Fig. 4 is desirable where floor space is a consideration, but the mode of operation is similar to that 90 shown in Figs. 1, 2.

Having thus described this invention, what I claim and desire to secure by Letters Patent is:

1. A rod mill comprising a casing; a rotary 95 drum having peripheral openings therein and mounted within said casing; a segmental apron in said casing adjacent the periphery of said drum; radially disposed fly bars on said periphery between said openings and cooperating with said apron and rods within said drum.

2. A rod mill comprising a casing; a rotary 105 drum in said casing having openings in the periphery thereof; transverse fly bars radiating from said periphery adjacent said openings; elevator humps on the interior of said drum adjacent said openings; a plurality of rods within said drum engaging said humps; a segmental apron in said casing; and shear 110 bars on said apron cooperating with said fly bars.

3. A rod mill comprising a casing having a partition therein; a segmental apron between 115 said partition and the adjacent wall of the casing; a rotary drum in said casing having openings in its periphery; fly bars on said periphery adjacent said openings and cooperating with said apron; and a plurality of rods within said drum.

In testimony whereof I have hereunto set my hand this 27th day of March, 1930.

CHARLES H. MACDONALD.
